WINDOW OF METAL OR SIMILAR MATERIAL IN METAL WALL

Gottfried Bruno Jonas and August Therman Eseling, Eindhoven, Netherlands, assignors to N. V. Philips' Gloeilampenfabrieken, Eindhoven, Netherlands

Application February 11, 1931, Serial No. 515,118
In the Netherlands March 25, 1930

3 Claims. (Cl. 250—35)

This invention relates to a window made of metal or similar material provided in a metal wall. Such windows are used in some discharge tubes, in which they serve for the passage of rays, for example, X-rays or cathode rays.

The provision of such windows which require as a rule an hermetic joint, is not always easy and especially when using very thin windows having, for example, a thickness of some hundredths of a millimeter, it is attended with difficulties.

The present invention has for its purpose to avoid these difficulties and concerns a metal or similar window in a metal wall, which window is fixed by fusing a binding agent consisting of a vitreous material which preferably surrounds the rim of the window.

A particularly durable arrangement is obtained if the window is provided in a recess or groove of the metal wall, which groove is entirely or partly filled with the vitreous binding agent.

There may also be provided a metal ring or locking-piece covering the rim of the window, a layer of the vitreous binding agent being interposed between such ring or locking-piece and the window. The provision of such a locking piece renders the joint more rigid and affords a certain protection at the same time.

By the invention it is rendered possible to use very thin windows which are extremely difficult if not impossible to secure in position in another way, for example, by soldering.

The material of which these windows are made may be capable per se of being fixed to the metal of the wall. If, however, the thickness of the windows is extremely small, sealing the window by fusing or welding its edge to the metal wall damages the window on account of the heat employed. This difficulty is avoided by the present invention and the risk of overheating the window may be further minimized by keeping the window in contact with a protective body, for example of graphite, during the mounting process whereby the temperature of the window is prevented from rising unduly.

The invention is also of great importance for windows consisting of a material which cannot be fixed by soldering or in a similar way, for example, windows consisting of graphite.

As a binding agent glass may be used, which is preferably of such a composition that its coefficient of expansion corresponds to the metal of the wall. When using a metal locking piece it is advisable to consider the coefficient of expansion. An excellent joint may be obtained, for example, if the metal wall and the locking piece consists of a chrome iron alloy.

The binding agent may also consist of enamel or similar mixtures.

The invention will be more clearly understood by reference to the accompanying drawing representing, by way of example, one embodiment thereof.

A metal portion 1 constituting, for example, the wall of a discharge tube for X-rays or cathode rays, is provided with an aperture 2 which is shut off by a thin window 3 consisting for example, of nickel having a thickness of some hundredths of a millimeter. The rim of this window engages a recess 4 in the wall and is hermetically connected to the metal portion 1 by means of a quantity of glass 5 which is fused between the wall of the window and the metal portion 1. The recess 4 serves at the same time to receive an annular locking piece 6, which is covered with glass and laid on the rim of the window 3 whereupon the glass is fused by heating, so that it melts together so as to form a compact intermediate substance. If this heating is effected in a flame, it is advisable to cover the window with a heat insulating body for example of graphite thus preventing the window from being unfavourably affected by the heating.

What we claim is:

1. A metal wall having an aperture, the wall at the edge of said aperture having a peripheral recess, a thin non-vitreous disc extending into said recess so as to form a window, a fused vitreous binding agent enclosing the peripheral edge of said non-vitreous window, and a metal ring in the recess, said binding agent adhering to the bottom and side walls of said recess and to the metal ring.

2. A metal wall having an aperture, the wall at the edge of said aperture having a peripheral recess, a metallic window closing said aperture, a metal ring overlying the edge of said window, and a vitreous binding agent enclosing the edge of said window and adhering to the walls of said recess and to the metal ring.

3. An electric discharge tube for emitting rays having a metal wall portion showing an aperture, a non-vitreous window overlying said aperture of said wall portion and permitting the passage of the rays, the wall at the edge of said aperture being formed with a recess, a metal piece disposed in said recess and spaced from the walls thereof, and vitreous binding material fused to the walls of the recess and the metal piece and surrounding the peripheral edge of said window, the window being disposed between said metal piece and the bottom of said recess.

CERTIFICATE OF CORRECTION.

Patent No. 2,000,845.

May 7, 1935.

GOTTFRIED BRUNO JONAS, ET AL.

It is hereby certified that error appears in the printed specification of the above numbered patent requiring correction as follows: Page 1, second column, line 33, claim 1, strike out the word "non-vitresys"; and that the said Letters Patent should be read with this correction therein that the same may conform to the record of the case in the Patent Office.

Signed and sealed this 11th day of June, A. D. 1935.
